UNITED STATES PATENT OFFICE.

AUGUST KADOW, OF TOLEDO, OHIO, ASSIGNOR TO THE VACUUM CASTING COMPANY, OF TOLEDO, OHIO, A CORPORATION OF OHIO.

AUTOMATIC CASTING MACHINE.

Application filed June 13, 1927. Serial No. 198,492.

My invention relates to an automatic casting machine, and more particularly to a machine for casting metal in permanent molds. My invention comprises a machine wherein a plurality of permanent molds are mounted upon a rotating support, the inlet opening in each mold is in the bottom thereof, and these inlets are dipped into molten metal as the molds are moved in succession past a supply thereof. Each mold is formed of an outer half movable radially of the rotary support upon which the mold is mounted, while the inner half is oscillatable about a horizontal pivot normal to the radius of said rotary support. The machine also comprises means for ejecting the casting from the inner mold half after it has been oscillated so as to face downward, means for die-trimming the discharged casting, means for cleaning the die, means for cooling the mold, means for drying the mold, the means for lubricating or smoking the mold.

The machine is particularly adapted for forming castings of shapes which are difficult to form, provision being made for completely filling mold cavities of such shapes. The machine is shown in the drawings and described in the following specification as adapted for forming battery grids, but it will be understood that many of the features of the machine are equally applicable to other castings.

Other features of the invention will appear as the description proceeds.

In the accompanying drawings forming a part of this specification, Figure 1 is a plan view of the casting machine proper, and a portion of the device for supplying it with metal, parts being omitted and parts being broken away; Fig. 2 is a vertical section substantially on the line 2—2 of Fig. 1; Fig. 3 is a partial vertical section and partial side elevation of the construction for supplying molten metal; Fig. 4 is an enlarged detail of a portion of the metal-controlling means; Fig. 5 is a partial section approximately on the line 5 of Fig. 1, illustrating the position of the mold as it is about to dip into molten metal; Fig. 6 is a partial section approximately on the line 6 of Fig. 1 showing the parts in a position assumed during the die-trimming operation; Fig. 7 is a partial section approximately on the line 7 of Fig. 1 showing the parts in the position assumed at the time of the discharge of the casting from the mold;

Fig. 8 is a partial elevation of the apparatus viewed from the right of Fig. 1; Figs. 9 and 10 are partial vertical sections approximately on the lines 9—9 and 10—10, respectively, of Fig. 2, showing the mold elevating slide; Fig. 11 is an enlarged view of the mold and associated parts in the dipping position, as shown at the right of Fig. 2; Fig. 12 is a view similar to Fig. 11, but showing the inner mold section in its discharging position; Fig. 13 is a vertical section of the inner mold carrier approximately on the line 13—13 of Fig. 11; Fig. 14 is an enlarged detail showing the mold-locking pin in a different position from that in which it is shown in Fig. 13; Fig. 15 is a vertical section through the inner mold half, showing the ejecting device; Fig. 16 is a detail section on the line 16—16 of Fig. 15; Fig. 17 is a plan view of a cam slide shown at the top of Fig. 13; Fig. 18 is an enlarged view of a portion of the left side of Fig. 2 showing a section of the outer mold and carrier therefor, and is on the line 18—18 of Fig. 19; Fig. 19 is an end view of a portion of the parts shown in Fig. 18, showing the adjusting valve dial; Fig. 20 is an enlarged section of the adjusting valve on the line 20—20 of Fig. 18; Fig. 21 is a view similar to Fig. 20, on the line 21—21 of Fig. 18; Fig. 22 is a view similar to Fig. 21, showing the valve in a different position; Fig. 23 is an enlarged horizontal section of the central drum on the line 23—23 of Fig. 2; Figs. 24 and 25 are enlarged detail vertical sections on the lines 24—24 and 25—25, respectively, of Fig. 23; Fig. 26 is an enlarged horizontal section of the central drum on the line 26—26 of Fig. 2; Fig. 27 is an enlarged plan view of the female die, parts being broken away; Fig. 28 is an enlarged plan view of the male die, parts being broken away; Fig. 29 is a side elevation of the male die; Fig. 30 is a vertical cross-section of the two dies; Fig. 31 is a vertical longitudinal section of the female die on the line 31—31 of Fig. 27; Fig. 32 is a somewhat diagrammatical view showing the central drum in cross-section and accessory devices in plan view; Fig. 33 is a section of the scraper and its supporting bracket on the line 33—33 of Fig. 32; Fig. 34 is an enlarged plan view of the scraper device; Figs. 35 and 36 are enlarged sections of the scraper device on the lines 35—35 and 36—36, respectively, of Fig. 33; Fig. 37 is an enlarged section through the cooling tank and related parts on the line 37—37 of Fig. 32.

32; Fig. 38 is a longitudinal section of the cooling tank on the line 38—38 of Fig. 37; Fig. 39 is a horizontal section substantially on the line 39—39 of Fig. 38; Fig. 40 is an enlarged detail of the cleaning burner on the line 40—40 of Fig. 38; Fig. 41 is an enlarged detail showing the manner of adjusting the elevation of the cooling tank; Fig. 42 is an enlarged elevation of the drying nozzle 10 and associated parts approximately on the line 42—42 of Fig. 32; Fig. 43 is an enlarged vertical section of the drying nozzle and its controlling parts; Fig. 44 is a cross-section of the drying nozzle on the line 44—44 of Fig. 43; Fig. 45 is a section on the line 45—45 of Fig. 32, showing the smoking burner and its control valve in elevation; Fig. 46 is a cross-section of the smoking burner on the line 46—46 of Fig. 45; Fig. 47 is a vertical section of the smoking burner on the line 47—47 of Fig. 46; Fig. 48 is a cross-section of the smoking burner on the line 48—48 of Fig. 47; Fig. 49 is an enlarged vertical section of the molds in casting position; Fig. 50 is an enlarged detail of a portion of the molding face of one of the molds. Fig. 51 is a further enlargement of a portion of the mating molds on the line 51—51 of Fig. 50; Fig. 52 is a section of the mating molds on the line 52—52 of Fig. 50; Fig. 53 is a view of a portion of the mating molds on the line 53—53 of Fig. 50; Fig. 54 is an enlarged face view of the inner mold on the line 54—54 of Fig. 49; Fig. 55 is an enlarged vertical section of the mold on the line 55—55 of Fig. 54; Fig. 56 is an enlarged horizontal section of a portion of the mold on the line 56—56 of Fig. 54; Fig. 57 is an enlarged face view of the outer mold section on the line 57—57 of Fig. 49; Fig. 58 is an enlarged vertical section of the outer mold half on the line 58—58 of Fig. 57; Fig. 59 is an enlarged partial horizontal section of the outer mold half on the lines 59—59 of Fig. 57.

45 My apparatus consists essentially of a turret machine A carrying permanent molds, a melting furnace and a delivering device B for melting metal and delivering molten metal to the molds, a scraping device C, a cooling tank D, and drying and lubricating apparatus E. The relation of these devices is clearly shown in Fig. 32.

55 The mold-carrying machine will be described first, the general construction being shown in Fig. 2. This machine comprises a base 100 having wheels 101 resting on tracks 102. From the base there rises a central drum 103 at the top of which there is a bearing cap 104 having a bearing 105 for the upper 60 end of a main drive shaft 106. Resting upon the upper face of cap 104 there is a plate 107 which supports a motor 108 for driving the apparatus. The motor is connected by a friction clutch 109 with main shaft 106.

65 The lower end of shaft 106 is mounted in a

downwardly projecting cone-shaped cap 110 having a bearing for the shaft at its apex. On the bottom end of shaft 106 there is a gear 111 meshing with a large gear 112 mounted on the lower end of a vertical counter-shaft 113. 70 Counter-shaft 113 is mounted in a bearing 114 and has a gear 115 on its upper end meshing with a rack 116 attached to a mold supporting base 117.

Attached to the base of the machine there 75 is an annular cam ring 118. Attached to the central portion of the drum there is an intermediate cam plate 119, and at the top of the drum there is a cam plate 120 bearing an inner cam 121 and an outer cam 122. A 80 face cam 123 is attached to the outer portion of cam 122 on the side of the machine where the molten metal is received.

Resting upon base 117 there is a series of 85 brackets 124, shown in plan in Fig. 1 and in detail in Figs. 5, 6, 7, 9, 10 and 26. Each bracket is held in position by a central dowel 125 and attaching bolts 126. There are as many of these brackets as there are molds used in the machine. Each bracket is provided with vertical guide grooves 127 in which there run tongues 128 on a vertical slide 129. A cam roller 130 carried at the bottom of each slide 129 runs in the groove of cam 118, so that the vertical position of 95 slide 129 is determined by cam 118.

A supporting bracket 131 for the inner mold half is attached to bracket 129 by means of bolts 132. Bracket 131 carries a pivot 133 about which the inner mold half 134 may 100 oscillate.

Slide 129 is provided with a horizontal slideway 135 in which there is a slide 136. Slideway 137 in bracket 131 is in line with slideway 135, and a slide 138 in slideway 105 137 is attached by an adjustable connection 139 to slide 136. Slide 138 carries a rack 140 in mesh with a gear segment 141 mounted on mold-carrying pivot 133. In another slide-way 142 in bracket 131 there is a slide 143 110 carrying the outer mold section. See Figs. 2 and 7. A cam roller 144 on slide 143 runs in cam 121. In the upper portion of bracket 131 there is a slideway 145 for a cam slide 146, which is controlled by a roller 147 running in cam 122. See Figs. 7 and 17.

Inner mold carrier.

The inner mold half 134 is provided with a boss 148 in which there is a socket 149 receiving the end of a mold supporting pin 150. See Figs. 2, 5, 6 and 49. The pin is held in place in the socket by a set screw 151. On mold pivot 133 there is a casting 152 provided with a socket 153 for receiving the 125 other end of pin 150. A locking pin 154 normally holds pin 150 in socket 153. A bell-crank shaped latch 155 is mounted on a pivot 156 and has one end 157 projecting into a slot in locking pin 154 and its other end 158 forms 130

a handle by which the cam can be moved against the pressure of spring 159 to release the locking bolt. Boss 148 is provided with grooves 160 into which tongues 161 on casting 5 152 project, in order to prevent any movement of the mold about the axis of the supporting pin.

Means for oscillating the inner mold half about axis 133 is shown in Figs. 2, 5, 6, 7, 11 10 to 14, and 17. Normally the mold is prevented from movement about pivot 133 by means of a locking pin 162 which passes through a hole 163 in bracket 131 into a socket 164 in casting 152. See Fig. 13. The locking 15 pin is operated by a lever 165 mounted on a pivot 166 in ears 167 attached to bracket 131. The lever may be secured to the pivot by means of set screws 168. The lower end 169 of lever 165 has a rounded part 170 fitting 20 in a groove 171 in the side of the locking pin. At the upper end of lever 165 there is a roller 172 operating in a cam groove 173 in a cam plate 174 attached to cam slide 146.

Ejector pins 175 pass through holes 176 25 in the inner mold half. See Fig. 15. The outer ends of holes 176 are provided with countersunk enlargements 177 in which operate plungers 178 carrying the ejector pins. Plungers 178 are attached to a frame 179 30 which has a boss 180. A socket 181 is provided in the mold section for a pin 182 having an end 183 projecting into the socket. A set screw 184 bears upon a bevelled seat 185 in end 183 of pin 182 and holds the pin 35 in position. Pin 182 projects through opening 186 in boss 180 on the plunger-carrying frame. The boss also carries a bearing for shaft 187 having a gear 188 meshing with teeth 189 on pin 182. Attached to one end 40 of shaft 187 there is a disc 190. An arm 191 is pivoted on shaft 187 and carries bolts 192 passing through slots 193 in disc 190, so that the arm is fixed in adjusted position relative 45 to the disc by tightening the bolts.

A lever 194 is pivoted at 195 on bracket 131. See Figs. 11 and 12. A pin 196 on the lower end 197 of lever 194 enters a slot 198 in the end of arm 191. The upper end 199 of lever 194 carries a cam roller 200 working in slot 50 201 in cam plate 174.

Shaft 187 is held in position by means of a collar 202 on the end opposite from disc 190, the collar being fastened in position by set screw 203. See Fig. 16.

Outer mold carrier.

The outer mold half 204 is provided with a boss 205 receiving a mold carrying pin 206. See Figs. 2, 7, 18 and 49. The pin is fastened 60 in position in the boss by means of set screw 207. Pin 206 enters opening 208 in carrier 143. Pin 206 is held in position in opening 208 by means of a latch pin 209. An operating member 210 pivoted at 211 has an end 65 212 entering in notch 213 in pin 209. The

other end of member 210 forms a handle 214 which is normally pressed outward by a spring 215 positioned against the handle and in a socket 216 in the mold carrier.

Vacuum connections.

70

A pipe 217 is connected with any suitable means for exhausting air and enters drum 103 and is attached to a lateral opening 218 in the drum. See Fig. 23. A ring 219 surrounds the drum and has a groove 220 at the elevation of hole 218. See Fig. 24. Packing rings 221 are provided between the drum and ring 219 above and below groove 220. Holes 222 through ring 219 connect groove 220 with a chamber 224 in a ring 223 surrounding ring 219. Ring 224 is fastened to carrier 117 by means of bolts 225. Carrier 117 is provided with a chamber 226. Elongated passages 227 open downward from chamber 223 and are always in register with openings 228 leading into cavity 226, so that cavity 226 is always in free communication with pipe 217. See Figs. 24 and 28.

Bracket 124 is provided with a projection 229 projecting into a relieved passageway 230 in slide 129. See Figs. 2 and 7. There is a passageway 231 in projection 229 mating with an outlet opening 232 from chamber 226. A hollow plug 233 enters passageways 231 and 232 and prevents leakage therebetween. The outer end of passage 231 is closed by plug 234, which has a flange provided with an upwardly opening hole 235 registering with an outlet opening 236 from passage 231.

Above outlet opening 236 there is a vertical passage 237 in slide 129. See Figs. 2, 9 and 10. A hollow pipe 238 fits into passage 237 and has on its lower end a nut 239. A spring 240 around pipe 238 presses nut 239 against projection 229 so that the end of pipe 238 is in substantially air tight contact with projection 229 regardless of vertical movement of slide 129.

On slide 129 there is a boss 241 having a lateral opening somewhat offset from passage 237, but connected therewith. A hollow plunger rod 242 has a substantially air tight fit within a guideway 243 in slide 143, and its end enters a chamber 244 in slide 143. See Figs. 7, 10 and 18. The other end of plunger 242 is provided with a collar 245 having a packing ring 246 adapted to contact boss 241. A spring 247 works within plunger 242 and bears against a pin 248 adjacent the end of the plunger. The other end of the spring enters a socket 249 in a lug 250 on slide 143 within chamber 244. The spring is kept from buckling by means of a hollow guide tube 251.

At the opposite end of chamber 244 from that entered by plunger 242 there is an adjusting valve. See Figs. 18 and 22. This valve comprises two discs and means for adjusting them. One of these discs 252 is held against rotation by a pin 253 passing through

130

the wall of slide 143 and entering a slot 254 in the edge of the disc. A flanged nut 255 is screwed into a threaded opening 256 at the ends of slide 143. The flange on nut 255 bears 5 against the edge of disc 252 and holds it against a shoulder 257 in the wall of chamber 244. Mating with disc 252 there is an outer valve disc 258. Disc 252 has a hollow projection 259 within which there is a stem 260 projecting from disc 258. Projecting in the opposite direction from disc 258 there is an operating stem 261 projecting outward through a packing gland 262 in nut 255. A spring 263, surrounding stem 261 presses 10 valve disc 258 against disc 252.

A hole 264 passes through disc 252. When disc 258 is in one position, a hole 265 in disc 258 mates with hole 264. Extending from hole 265 on the side of disc 258 against disc 20 252 there is a groove 266. This groove extends around the axis of the disc so that it continues to register with hole 264 when disc 258 is turned. Groove 266 lessens in cross-section as it extends away from hole 265, so 25 that the passageway through the discs is not only baffled but lessened in cross-section as hole 265 is turned away from hole 264. On the outer end of stem 261 there is an indicating disc 267 having graduated marks there- 30 on, so as to indicate the exact position of disc 258 with respect to disc 252.

Holes 268 pass through the flange of nut 255 into a channel 269 surrounding that flange. Channel 269 opens into a chamber 35 270 in the downwardly directed part of bracket slide 143. At the bottom of chamber 270 there is an operating valve 271 adapted normally to rest against a seat 272. Valve 271 is provided with a stem 273, and is normally held seated by a spring 274. A bell-crank lever 275 is pivoted at 276 in position so 40 that one arm 277 contacts valve stem 273. The other arm 278 of lever 275 carries a set screw 279.

Member 131 is provided with a bracket 280 having therein a horizontal slideway 281. A cam roller 282 is carried by a stem 283 working in slideway 281. The other end of stem 283 is provided with a collar 284, and a spring 285 normally presses the cam roller away 50 from bracket 280. A pin 286 is fixed in bracket 280 and extends into the head carrying cam roller 282 in order to keep its stem from turning in bearing 281. Set screw 279 in arm 278 55 is in line with stem 283 and is contacted thereby when valve 271 is to be opened. Within member 143 below valve 271 there is a passage 287.

In the construction shown, the bottom end 60 of this passage is closed by means of a plug 288, but there is a lateral opening 289 from passage 287 into the hollow pin 206. The mold is provided with a recess 290 forming a continuation of the passage in pin 206, and 65 from this opening there radiate two passages

291 diagonally towards the upper portion of the mold. See Fig. 57. The ends of passages 291 are closed by plugs 292, but they connect with a horizontal groove 293 in the face of the mold by means of openings 294. In the construction shown, a block 295 is provided in groove 293 and held therein removably by screws 296. The block does not completely fill the groove, but leaves a space 297 back of the block and a slit 298 above the block. 75

The inner mold half is provided with a groove 299 in its face mating with groove 293. See Fig. 54. At each end of groove 299 there is a vertical continuation 300 towards the bottom of the mold. 80

In the construction shown, the mold cavity 301 is shaped to form a battery grid. For this purpose it is provided with central vertical grooves 302 for forming the central bar of the grid, grooves 303 for forming end bars of the 85 grid, horizontal grooves 304 for forming horizontal bars of the grid, and intermediate grooves 305 for forming the intermediate bars of the grid. These intermediate bars are of considerably less thickness than the 90 other bars, and in the construction shown the cavity is shaped so that these bars are offset, there being raised portions 306 on each mold adapted to partially enter the grooves 305 on the mating mold member in the manner clearly shown in Fig. 52. In the construction shown there is a projection 307 entering into the top of groove 302, forming a notch in the top of the central bar. 95

Above the mold cavity the face of the outer mold is ground away for a short distance, as indicated at 308, and similarly the face of the inner mold half is ground away at 309, this ground away portion extending, in the construction shown, about half way from the 100 mold cavity to groove 299 in the inner mold section. See Figs. 54 and 58. Above this ground away portion 308 the outer mold face is flush up to slit 298 above block 295. The inner mold section has a baffle portion 310 110 above grooves 302, which is flush with the plane of the face and contacts the face of the outer section, but at the ends of this portion 310 the inner mold section is ground away so as to form a slit extending from groove 299 115 to the space formed by relieved portions 308 and 309. At the ends of the mold space the face of the inner mold section is ground away at 311 to an appreciable extent, and between this portion 311 and vertical grooves 300 the 120 surface 312 is ground away to a less extent, so as to form a comparatively narrow slit between the mold sections when the mold faces are brought together.

Below the mold cavity and in outer mold 125 section there is a downwardly widened inlet relief portion 313, and between that and the mold cavity a comparatively shallow relief 314. On the face of portion 313 there are ridges 315, the bottoms of which are directed 130

towards the end of the mold which is ahead when the machine is in operation. The inner mold half is provided with a similar inlet construction comprising the bevelled portion 316, the inlet slot portion 317 and ridges 318 adapted to mate with ridges 315 when the mold sections are brought together.

Metal supply.

10 In order to supply molten metal to the molds there is provided a melting furnace 319 containing a crucible 320. See Figs. 1, 2, 3, 4, 8 and 32. The furnace may be heated in any desired manner, an opening 321 being shown 15 in the construction illustrated for receiving the burner. Crucible 320 has a cover 322 provided with a flue 323 for conducting away fumes from the metal. A series of rollers 324 form a chute over which ingots 325 may be 20 rolled into the crucible by any desirable mechanical means, not shown. Within the crucible there is provided a float 326. On cover 322 there is mounted a switch 327 adapted to control the motor, not shown, for feeding the 25 ingots into the crucible. A lever 328 is pivoted at 329 to cover 322 and is normally held down by an adjustable weight 330. A plunger 331 rests upon float 326 and works through a suitable bearing in cover 322. Lever 328 30 is provided with a set screw 332 in line with switch 327 and a set screw 333 in line with plunger 331.

Between the molding apparatus and the melting furnace there is a working pot 334 resting upon a furnace 335 adapted to keep the metal in the working pot molten. A floating cover 336 is provided in the working pot, and has therein a slot 337 through which the bottom ends of the molds may dip into 40 the molten metal in the pot.

Brackets 338 are attached to the under side of the pot furnace, and set screws 339 working through brackets 338 rest upon rails 102, so that the furnace is adjustably seated upon 45 the rails.

At various points around the working furnace there are plungers 340 working in bearings 341 on the furnace frame. Set screws 342 in the upper ends of these bearings support the working pot. The lower ends of 50 the plungers rest upon rollers 343 carried by arms 344 extending from rock shafts 345 mounted in bearings 346 on the pot furnace. One of the rock shafts 345 is provided with 55 an adjusting lever 347. Arms 348 projecting downwardly from shafts 345 are connected by links 349 so that the various rock shafts 345 oscillate together. In fixed position adjacent lever 347 there is a ratchet 350 60 with which co-operates a catch 351 on the lever. A spring 352 normally holds the catch in engagement with the ratchet. A link 353 extending from catch 351 to a suitable operating handle, not shown, enables the catch 65 to be disengaged from the ratchet and the

lever moved to oscillate the rock shafts and adjust the working pot when desired.

Cover 336 of the working pot has a receiving opening 354 beneath the end of a discharge trough 355 leading through the wall 70 of furnace 319 from a discharge spout 356 from the crucible. The discharge opening 357 in the wall of the crucible, leading into the discharge spout 356, is controlled by a valve plunger 358.

Arms 359 are rigidly attached to the floating cover 336 and receive a pivot rod 360 through slots 361. A U-shaped valve-operating member 362 is mounted on the ends of pivot rod 360. The pivot rod is held against lateral movement by being positioned in slots 363 in brackets 364 on the working pot. A set screw 365 passes through an arm of member 362 and rests upon arm 359. The closed end of the U-shaped member is provided with a roller 366 in position to bear against a flat head 367 on the end of plunger 358. A spring 368 normally presses plunger 358 outward so that its head 367 contacts roller 366.

Trimming dies. See Figs. 6, 7, and 27 to 32.

Attached to mold support 117 there is a bracket 369 for supporting a female die. Die frame 370 rests upon bracket 369 and has parallel ears 371 at each end thereof, there being slots 372 between the ears. Bolts 373 pass through these slots into the bracket. On the outer sides of the ears there are mounted on the bracket pins 374, and set screws 375, passing through these pins and bearing against the ears, accurately adjust the frame upon the bracket. A female die plate 376 with a die opening 377 is fastened to frame 370 by means of bolts 378.

A male die carrier 379 is provided above the female die. A stem 380 is provided for supporting die carrier 379, and a socket 381 in the die carrier receives a head 382 of the stem. Screws 383 fasten the head in position in the socket. To the under side of the die carrier there is fastened a male die plate 384 by means of screws 385.

At the sides of the die plate there are holding plates 386. Screws 387 passing through slots 388 in plates 386 hold the plates against the sides of the die carrier, but allow vertical movement thereof. At the ends of the die carrier there are provided blocks 389 to which the side plates are fastened by means of screws 390. Extending from the die carrier above the side plates there are perforated lugs 392 having stop nuts 393 adjustably positioned in the upper ends thereof. Grooved blocks 394 rest upon the upper edges 115 of the die plates, and springs 395 fitted within perforated lugs 392 normally press grooved heads 394 downward, and so normally maintain the side plates at the lowest position allowed by slots 388. Mold car- 120

rying casting 152 is provided with a socket for receiving stem 380. The casting may be slit at 396 so that it can be tightened upon the stem by bolts 397. Ears 398 project from the ends of the die carrier and have downwardly directed centering pins 399 adapted to enter holes 400 in the female die plate 376 and insure proper registration of the dies.

10 *Die cleaner. See Figs. 32 to 36.*

Attached to the machine base 100 there is a bracket 401 having a block 402 mounted thereon by a tongue and groove connection 15 403 so that the block may be moved towards or from the axis of the mold carrier, but is held firmly against movement about the axis of the mold carrier. Machine base 100 is provided with a groove 404 into which a tongue 20 405 of bracket 401 projects, and the bracket may be held in adjusted position by means of set screws 406 bearing against tongue 405.

Brush carriers 407 are fastened to block 402 by means of bolts 408. Suitable brushes 25 409 project downward from carriers 407.

Between carriers 407 there is a scraper carrier 410 which fits into a groove 411 in block 402, and is fastened in position by bolts 412. Carrier 410 has a scraper knife 413 fastened 30 to its under side by means of bolts 414. Scraper knife 413 has a bevelled edge 415, as clearly shown in Fig. 36.

Mold cooler. See Figs. 32 and 37 to 41.

35 A bracket 416 is provided with a tongue 417 fixed in position in groove 404 by means of set screws 418. The outer end of the bracket is recessed at 419. A plate 420 is provided with slots 421 through which bolts 422 pass 40 into the recessed end of bracket 416 and secure the plate in vertically adjusted position against the bracket.

A tank 423 is mounted upon a supporting slide 424. A journal 425 is provided in the 45 lower end of slide 424, and a bolt 426 passes through a horizontal slot 427 in plate 420 and enters journal 425 eccentrically of the journal. A segment 428 is mounted upon the journal and is held by a bolt 429 from 50 turning about the journal. The segment is provided with a series of holes 430. A crank 431 is attached to the end of the journal, and the handle 432 of the crank has a locking pin 433 projecting therefrom towards the segment. A stem 434 projects from the locking pin through the handle and is provided at 55 the outer end of the handle with a knob 435 for manipulating the locking pin against the pressure of a spring 436 surrounding the stem and normally pressing the locking pin into a hole in segment 428.

The tank is provided with an inlet nozzle 437 having a comparatively small opening therein. Surrounding the upper edge of the

tank there is an overflow trough 438 provided 65 with an outlet pipe 439.

Through a central opening 440 in the tank there project vertical pipes 441 having horizontal perforated ends 442. The pipes are held in adjusted position by means of clamping bars 443 applied to the sides of the pipes and held in clamping position by means of bolts 444 passing through the bars into plate 420. The ends 442 of the pipe are held in central position at the ends of the tank by 75 centering pins 445. The outer walls of trough 438 is provided at its ends with notches 446 for the passage of the mold bottoms. The trough on the side next to the axis of the machine is provided with a higher wall 447 80 in order to prevent, as far as possible, any spraying of the water in this direction.

A thermostat 448 projects into the side of the tank, and the bottom of the tank is recessed at 449 in order to provide a supply of 85 water surrounding the casing of the thermostat. The thermostat controls a pump 450 which supplies water to the tank.

Drier. See Figs. 32 and 42 to 44.

90 A bracket 451 has a tongue 452 entering groove 404 and fastened in adjusted position by means of set screws 453. On the outer end of the bracket there is a valve casing 454 fed by a pipe 455 and having a vertically extending outlet pipe 456 leading to a discharge nozzle 457. In the construction shown, nozzle 457 is provided with lower perforations 458 substantially on a level with the bottom of the mold, and upper perforations 459 slanting downward towards the bottom of the mold.

95 Within valve casing 454 there is a valve 460 having a stem 461 extending through the end of the valve casing towards the axis of the machine, and having a block 462 mounted on the end of the stem. A spring 463 pressing against block 462 normally forces the block towards the axis of the machine and seats the valve. A cam plate 464 is secured in a groove 100 in the outer edge of the supporting bracket for the female die member, by means of a set screw 465. Cam plate 464 is on a level with block 462.

Lubricator. See Figs. 32 and 45 to 48.

115 Mounted upon the same bracket with valve casing 454 there is a similar valve casing 466 fed by a pipe 467 and having a vertical outlet pipe 468 leading to a burner 469.

120 In the construction shown, this burner head comprises a central block 470 having vertical grooves 471 in the sides thereof. Nozzle plates 472 provided with flanges 473 are arranged on the sides of the main block so that a slit 474 is provided between these flanges in register with grooves 471. Plates 472 are provided with slots 475 through which

- bolts 476 pass into the central block, so that the plates may be secured in adjusted position. A top plate 477 is attached to the block by means of bolts 478.
- 5 A holder 479 is secured in adjusted position on pipe 468 by means of a set screw 480. Holder 479 has attached thereto pipes 481 leading to pilot burner cocks 482 directed upwardly towards the outlet slits 474 from the 10 main burner.

Oiling system.

- The various parts of the machine may be supplied with oil in any suitable manner, but 15 in the construction shown the lower part of the machine is lubricated from an oil supply pipe 483 leading to an opening 484 in drum 103. Opening 484 leads into a groove 485 in carrier 117, and downwardly directed 20 grooves 486 lead from groove 485 to a trough 487 in which gear rack 116 runs. Oil in trough 487 may enter countershaft 115 through lateral openings 488. Surplus oil 25 is drained from the lower bearing of shaft 115 by pipe 489 leading to the lower bearing for main shaft 106. Oil from this latter bearing may be discharged by a pipe 490 and return to circulation or to a cleaning device, or to a waste tank, as desired.

30

Operation.

- The main features of the operation of the apparatus can be easily understood from the foregoing description of the construction 35 thereof; but a brief résumé of the operation may be an aid to the complete understanding of the apparatus.

During the normal operation of the apparatus motor 108 rotates continuously, and 40 through shaft 106 and countershaft 115 drives the mold carrier 117 continuously. As the mold carriers rotate, the molds go through the same movements in succession, so that the movements of one mold head only need be described. The mold and its operating parts are all carried by the vertical slide 129, whose 45 vertical position is determined by roller 130 running in cam 118. By means of movement relative to this cam, the mold is raised and lowered in a manner which will appear as the description proceeds.

Starting with the mold in the position in which it is shown in Fig. 5, closed and ready 55 to receive a charge, the rotation of the mold carrier causes cam roller 130 to run down the cam way, as clearly indicated in Fig. 5, and thereby lowers the mold until its lower end dips into the molten metal in groove 337 in float 336. At the same time cam roller 282 60 comes in contact with cam 123 and moves the roller carrying stem out against set screw 279 and thereby operates valve 271 to an extent determined by the shape of cam 123 and the adjustment of set screw 279. The 65 opening of valve 271 connects the mold cavity

with exhaust pipe 217 through connections which will be readily understood from the detailed description of the vacuum connections. It will be understood that substantially constant vacuum is maintained in chamber 244 in carrier 143. During the movement of the mold, while valve 272 is closed, chamber 270 becomes exhausted to substantially the same extent as chamber 244. When valve 271 is opened the air rushes from the intermediate grooves and the mold chamber into chamber 270, immediately reducing the air pressure in the mold chamber enough to start flow of molten metal upward into the chamber. During the continued movement of the so mold with its inlet opening dipped in the molten metal, air is exhausted from chamber 270 into chamber 244 through the adjusting valve comprising discs 252 and 258. It will be readily understood that the speed at which 85 air is exhausted from chamber 270 will be dependent upon the adjustment of the adjusting valve, being comparatively rapid if holes 264 and 265 are in alignment, and being progressively less rapid as disc 258 is turned so 90 as to bring a narrower portion of groove 266 in alignment with opening 264.

The manner in which the air is exhausted from the mold cavity in the mold shown is particularly effective in quickly filling the 95 mold, without leaving any defective portions, and without resulting in the flow of molten metal into the exhaust passages. It will be noted that raised portion 310 on the inner mold prevents molten metal, entering 100 along the central-bar-forming groove 302, from passing directly upward into the vacuum groove. The use of block 295 results in the distribution of the air along slit 298 when it is exhausted from groove 299, so that 105 there is no material tendency for the metal to be drawn directly towards vacuum openings 294 more than towards other portions of the vacuum grooves. Block 295 is additionally advantageous because, in case of an 110 imperfectly closing mold resulting in access of the liquid to the vacuum grooves, the block tends to prevent entrance of the metal to the exhaust passages. Any small amount that may be drawn in through slit 298 solidifies in 115 chamber 293, and removal of block 295 enables groove 293 to be quickly and easily cleaned. Comparatively serious difficulty would arise if the metal could be drawn directly into passages 291.

In this way the degree of vacuum in the mold cavity during the principal part of the filling of the mold, and especially during the latter part of the filling of the mold, can be very accurately adjusted. This is a very 125 desirable feature, as defective castings result from a vacuum so low as to fail to completely fill the mold cavity, or from a vacuum so high as to cause the too rapid filling of the cavity, resulting in the filling of the upper portion 130

of the cavity before all of the intermediate sections are filled.

As the mold approaches the end of the groove 337 in float 336, cam roller 130 runs up a sufficient elevation in cam 118 to raise the mold above the edge of the working pot. The width of the opening in the bottom of the mold and the temperature of the mold, especially the bottom thereof, is regulated so that the metal will not flow out of this inlet opening after the mold is lifted from the bath of molten metal. This feature is fully disclosed in my Patent #1,606,236, issued November 9th, 1926, and need not be further discussed at this point.

It will be readily understood that the ridges 318 upon the mold sections, forming slanting partitions across the inlet opening, act as scoops to aid in raising the metal from the bath into the mold, and are particularly useful in insuring the prompt and complete filling of the inlet opening by molten metal.

After the mold has rotated a sufficient distance to insure the proper solidification of the casting in the mold, roller 144 enters an outwardly directed run in cam 121, indicated at 491 on Fig. 1. This forces the carrier 143 of the outer mold half outward away from the inner mold half. It will be readily seen from a comparison of the faces of the inner and outer mold halves, shown respectively in Figs. 54 and 57, that there is an overcast in the inner mold half in portions 309 and 311 outside of the regular mold cavity, whereas there is no such overcast in the outer mold half. This insures that when the mold halves are separated the casting will remain in the inner mold half. This same result could be brought about in other ways, as by forming portions of the grooves in the inner mold half with less bevel or relief on their sides. The casting will remain in the inner mold half rather than moving outward with the outer mold half if the cavities are shaped so that the casting will bind more on the inner mold half than it does on the outer mold half.

At about the time the outer mold section is moved outward, cam roller 147 enters a runway 492 in cam 122, which draws slide 146 towards the axis of the mold and results in moving cam groove 173 so that cam wheel 172 is moved to the position shown in Fig. 14, thereby unlocking the oscillatable carrier for the inner mold section. Immediately after the outer mold section is moved outward, and while the inner mold section is unlocked, a cam wheel 493 on slide 136 enters a runway 494 in cam 119, which drives the slide outward away from the axis of the machine, and thereby oscillates the mold about its pivot 133 to the position in which it is shown in Fig. 12. At the same time the mold is lowered, by cam wheel 130 running

into a downward run of cam 118, until the face of the mold is just above female die plate 376. Thereupon cam roller 147 runs into an outwardly directed run 495 of cam 122 which moves the parts to the position in which they are shown in Fig. 12, thereby oscillating lever 194 and projecting the ejector pins downwardly and loosening the casting from the inner mold half so that it rests upon the female die plate. The mold face is in such close juxtaposition to the die plate at this time that the casting is very accurately positioned on the die plate. As clearly appears from Fig. 1, the outward run 495 is comparatively short so that the ejector pins are promptly returned to their normal position after the plate is discharged and the mold is again unlocked by inward run 496 of cam 122. Immediately thereafter the mold is oscillated about its pivot 133 to its normal position by inward run 497 of cam 119. Thereafter the mold is again locked in position by the outward run 498 of cam 122, returning the cam slide controlling the locking pin and the ejector pins to the normal position in which it is shown in Fig. 11. When the ejector pins are retracted, pin 196 is in line with axis 133, so that oscillation of the mold carrier does not affect the position of the ejecting pins.

Immediately after these operations, cam roller 130 enters another downwardly directed run of cam 118 and lowers the male trimming die upon the casting. It will be readily understood that the plates 386 first contact the sides of the casting, after which springs 395 yield during the continued downward travel of the male die. Centering pins 399 enter holes 400 in plate 376 and insure the accurate registry of the two dies. The casting is thus forced downward by the male die through the female die and trimmed accurately.

It will be readily understood that any failure to completely fill the mold cavity is most apt to occur at the edges of the casting, and by providing an overcast in relieved portions 309 and 311 of the inner mold, and trimming off this overcast portion, a high percentage of perfect castings results. After the trimming operation just described, the mold is once more raised so that the male die will move over the top of scraper and brush carriers 407 and 410, while the female die plate moves beneath these carriers and is subjected to the brushing action of brushes 409 and the scraping of knife 413. The bevelled edge 415 of knife 413 insures that any scrap metal on the female die plate will be scraped off therefrom, without cutting the face of the die.

Immediately after the scraping operation, the mold passes over tank 423, and during its passage over this tank roller 130 enters a downward run in cam 118 and lowers the bot-

tom of the mold into the water in the tank. The temperature of the water to which the mold is subjected is controlled by thermostat 448, so that the temperature of the gate portion of the molds can be accurately regulated at this point.

At the same time that the bottom of the mold is being cooled by dipping in the water in the tank, the face of the mold thereabove 10 is subjected to flames from gas issuing through the perforations of pipe ends 442. These burners not only prevent excessive cooling of the mold cavities, but also clean the mold surfaces by melting off any metal 15 which may accidentally adhere thereto. In this way the body of the mold may be maintained at a higher temperature than the gate of the mold, in spite of the fact that the gate is dipped in the molten metal while gathering 20 the charge.

After the molds leave the cooling tank they pass drying nozzle 457, cam plate 464 being so adjusted as to open valve 460 just as the mold passes the nozzle. The air projected 25 from the nozzle efficiently dries the lower part of the mold, and avoids any uneven cooling of this portion of the mold because of the retention of water thereon after it leaves the cooling tank, and also presents the mold in 30 proper condition for receiving a lubricating coating.

In order to prevent sticking of the casting to the mold, it is preferable to lubricate the mold faces. This may be done in various 35 ways, but I prefer to do it by means of a smoking flame. Pilot lights from cocks 482 burn continuously and ignite the fuel from slits 473 when the controlling valve is opened by cam plate 464, which occurs just as the mold 40 comes opposite the burner. It will be obvious that a series of molds are arranged upon the carrier, so that they pass the drying and smoking devices in rapid succession, and, therefore, the automatic valves for opening 45 and closing these devices each time a mold passes the same may be omitted if desired.

After the mold passes the smoking burner, an inward run 499 of cam 121 moves the outer 50 mold section against the inner mold section. In the construction shown, cam roller 144 is directly attached to a member 500, which is normally pressed by a spring 501 outward against a stop shoulder 502 on slide 143. In 55 other words, slide 143 is normally held by spring 501 as far inward as is permitted by member 500. It will be readily understood that, in case of any object being positioned between the mold halves when the slide operates to close them, spring 501 yields sufficiently to prevent the breakage of any part. Furthermore, spring 501 may be made light enough so that in case a workman's hand is caught between the closing mold sections the 60 spring will yield without material injury to

the workman. After the molds are once closed and vacuum is applied, it will be readily understood that the vacuum holds the mold halves firmly together. If desired, the apparatus may be constructed without spring 70 501 and operated so that the mold is definitely closed and then the controlling cam is slightly relieved, providing for any necessary yielding of the outer mold section during the casting operation.

The raising and lowering of the mold is not extensive. If desired, the cams 119, 121 and 122 may be formed to vary in a vertical plane the same as cam 118, so that the rollers will be always similarly positioned in the cam 80 tracks irrespective of the elevation of the mold; but it is considered preferable to make the cam grooves and rollers of such an extent vertically that the mold can be moved up and down as much as is necessary without interfering with the proper co-operation of the cam rollers with cams 119, 121 and 122. Similarly, the face of cam 123 is made broad enough to insure the contact of the co-operating cam roller therewith regardless of vertical movement of the mold. In order to avoid friction, it is preferable to enlarge the upper part of the grooves in cams 119, 121 and 122, as shown at 503.

When metal is taken from the working pot 95 so as to lower the floating cover thereof, the cover and arms 359 and 362 swing about pivot 360 so as to allow valve plunger 358 to move outward from opening 357, and molten metal flows from the melting crucible through spout 356, trough 355 and opening 354 into the working pot. Set screw 365 may be adjusted 100 so as to open the valve a sufficient amount to keep the metal at the desired working level in the pot.

If for any reason it is desired to dip the mold to a greater or less extent into the metal, or if a longer or shorter mold is used, adjustment may be made quickly by means of lever 347 raising or lowering the working 110 pot with respect to the melting furnace. While screws 342 might be used for adjusting the height of the working pot, they are used rather for the purpose of leveling the pot than for adjusting its elevation. Similarly, screws 339 may be used for adjusting 115 the height of the working pot furnace, but this is not necessary in ordinary operation of the machine.

Melting furnace 319 is likewise mounted 120 upon adjusting and leveling screws 505, but manipulation of these screws is seldom necessary during the normal operation of the machine.

When the molten metal in crucible 320 is 125 lowered so that float 326 and plunger 331 allow lever 328 to close switch 327, a suitable motor is energized and feeds ingots over rollers 324 until the level of the molten metal in the crucible is raised enough to raise float 130

326, plunger 331 and lever 328, and allow switch 327 to open. Manipulation of weight 330 and adjusting screws 332 and 333 enables the operator to determine the minimum head 5 of molten metal above opening 357 which will close the switch and feed in another ingot.

The construction shown is particularly adapted to mold battery grids of lead or lead alloy. It is particularly desirable to have the 10 working pot substantially covered when dealing with lead and to direct the fumes of the melting furnace away from the factory room. As a further protection against fumes from the melting furnace and against disagreeable 15 heat therefrom, a shield 504 may be provided between the melting furnace and the casting room.

While the apparatus has been shown and described as particularly adapted for the 20 manufacture of lead battery grids, it will be understood that objects of different shapes may be manufactured by suitable changes in the shape and operation of the mold, and that molten metals other than lead may be cast 25 in the same manner, suitable changes being made in the heating, cooling and timing of the mold.

Other changes in the construction shown may be made within the scope of the 30 appended claims.

What I claim is:

1. Apparatus for casting fluid metal, comprising a container for molten metal, a mold having an inlet opening in its under side, 35 means to move the mold in a circular path, part of said path being over the container, means to dip the inlet of the mold into metal in the container while thereover, and connections whereby air is exhausted from the mold 40 cavity while the inlet is dipped into the molten metal.

2. Apparatus for casting fluid metal, comprising a container for molten metal, a mold having an inlet opening in its underside, 45 means to move the mold in a closed path, part of said path being over the container, means to dip the inlet of the mold into metal in the container while thereover, the moving and dipping devices being connected to dip 50 the mold while it is moving over the container, and connections whereby air is exhausted from the mold cavity while the inlet is dipped into the molten metal.

3. Apparatus for casting fluid metal, comprising a container for molten metal, a mold having an inlet opening in its under side, 55 means to move the mold in a closed path, part of said path being over the container, means to dip the inlet of the mold into metal in the 60 container while thereover, connections whereby air is exhausted from the mold cavity while the inlet is dipped, and means to cool the walls of the mold surrounding the inlet.

4. Apparatus for casting fluid metal, com-

prising a container for molten metal, a mold 65 having an inlet opening in its under side, means to move the mold in a closed path, part of said path being over the container, means to dip the inlet of the mold into metal in the container while thereover, connections whereby air is exhausted from the mold cavity 70 while the inlet is dipped, a container for cooling fluid beneath the path of the mold, and means to dip the inlet of the mold into the cooling fluid as it passes over the container 75 for said fluid.

5. Apparatus for casting fluid metal, comprising a container for molten metal, a mold having an inlet opening in its under side, 80 means to move the mold in a closed path, part of said path being over the container, means to dip the inlet of the mold into metal in the container while thereover, connections whereby air is exhausted from the mold cavity 85 while the inlet is dipped, a container for cooling fluid beneath the path of the mold, means to dip the inlet of the mold into the cooling fluid as it passes over the container for said fluid, and means for automatically controlling the temperature of the fluid in said container. 90

6. Apparatus for casting fluid metal, comprising a container for molten metal, a mold having an inlet opening in its underside, 95 means to move the mold in a closed path, part of said path being over the container, means to dip the inlet of the mold into metal in the container while thereover, connections whereby air is exhausted from the mold cavity while the inlet is dipped, means to cool the walls 100 of the inlet opening while the mold is empty, and means for heating the walls of the casting cavity of the mold. 105

7. Apparatus for casting fluid metal, comprising a container for molten metal, a mold having an inlet opening in its under side, 110 means to move the mold in a closed path, part of said path being over the container, means to dip the inlet of the mold into metal in the container while thereover, connections whereby air is exhausted from the mold cavity while the inlet is dipped, means to cool the walls 115 of the inlet opening while the mold is empty, and means for heating the walls of the casting cavity of the mold while cooling the walls of the inlet opening.

8. Apparatus for casting fluid metal, comprising a container for molten metal, a mold having an inlet opening in its under side, 120 means to move the mold in a closed path, part of said path being over the container, means to dip the inlet of the mold into metal in the container while thereover, connections whereby air is exhausted from the mold cavity while the inlet is dipped, a container for cooling fluid beneath the path of the mold, means to dip the inlet of the mold into the fluid while 125 the mold is over the container, and a burner

adapted to apply flame to the walls of the casting cavity of the mold while the inlet of the mold is in the cooling fluid.

9. Apparatus for casting metal, comprising a container for molten metal and a cover for the container floating on the metal therein and having an opening therethrough, a mold having an inlet opening in its bottom, and means to dip the bottom of the mold 10 through said opening into the molten metal in the container.

10. Apparatus for casting metal, comprising a container for a supply of molten metal, a working pot, a cover for the pot adapted to 15 float on molten metal in the pot, a valve controlling flow of metal from the container to the pot, and connections between the float and the valve opening the valve as the float is lowered and closing the valve as the float is raised.

20 11. Apparatus for casting metal, comprising a container for a supply of molten metal, a working pot, a cover for the pot adapted to float on molten metal in the pot, a valve controlling flow of metal from the container 25 to the pot, connections between the float and the valve opening the valve as the float is lowered and closing the valve as the float is raised, there being an opening through the float, a mold having an inlet opening in its 30 bottom, and means to dip the bottom of the mold through the opening in the float.

12. Apparatus for casting fluid metal, comprising a container for molten metal, a cover for the container having therein an arcuate 35 slot, a mold having an inlet opening in its bottom, means to move the mold continuously in a path a portion of which is over said slot, and means for dipping the bottom of the mold 40 through said slot into molten metal in the container while the mold is travelling over said slot.

45 13. In apparatus for casting metal, a container for molten metal, a mold having an inlet opening in its bottom, and means to revolve the mold in a path passing over the container and dip the bottom of the mold into the metal in the container as it passes 50 thereover, the mold comprising two mold halves mating in a plane tangential to said path.

55 14. In apparatus for casting metal, a container for molten metal, a mold having an inlet opening in its bottom, means to revolve the mold in a path passing over the container and dip the bottom of the mold into the metal in the container as it passes thereover, the mold comprising two mold halves mating in an approximately vertical plane, means to slide one mold half rectilinearly towards and 60 from the other, and means to swing the other mold half about a horizontal axis to swing its mating face from an approximately vertical plane downward to an approximately horizontal plane.

65 15. In apparatus for casting metal, a con-

tainer for molten metal, a mold having an inlet opening in its bottom, means to revolve the mold in a path passing over the container and dip the bottom of the mold into the metal in the container as it passes thereover, the 70 mold comprising two mold halves mating in an approximately vertical plane, and means to slide one mold half rectilinearly towards and from the other, and means to swing the other mold half about a horizontal axis to 75 swing its mating face from an approximately vertical plane downward to an approximately horizontal plane, the mold cavity being so shaped that the casting binds more in the swinging half than in the sliding half. 80

16. In apparatus for casting metal, a container for molten metal, a mold having an inlet opening in its bottom, means to move the mold over the container and dip its bottom into the molten metal in the container, 85 means to discharge the casting from the mold, a female die in position to receive the discharged casting, and a male die adapted to force the casting through the female die and thereby trim the casting. 90

17. In apparatus for casting metal, a mold comprising two mold halves mating in a substantially vertical plane, means to slide one mold half rectilinearly towards and from the other, means to swing the other mold half 95 about a horizontal axis to move its mating face from a vertical plane downward to a horizontal plane, a female die beneath the horizontal position of the swinging mold face, a male die movable about the same pivot 100 as the mold half, and means to raise and lower the pivot.

18. Apparatus for casting fluid metal, comprising a container for molten metal, a mold having an inlet opening in its under side, 105 means to move the mold in a closed path, part of said path being over the container, means to dip the inlet of the mold into metal in the container while thereover, connections whereby air is exhausted from the mold cavity 110 while the inlet is dipped, a container for cooling fluid beneath the path of the mold, means for automatically controlling the temperature of the fluid in said container, means to dip the inlet of the mold into the cooling fluid 115 as it passes over the container for said fluid, and means for thereafter applying a smoking flame to the walls of the mold cavity before the mold again reaches the metal container.

19. Apparatus for casting fluid metal, comprising a container for molten metal, a mold having an inlet opening in its under side, means to move the mold in a closed path, part of said path being over the container, means to dip the inlet of the mold into metal in the 125 container while thereover, connections whereby air is exhausted from the mold cavity while the inlet is dipped, said connections comprising a vacuum passage in a carrier for the mold, a valve adjustable to provide an open- 130

ing of the desired size in said passage, a valve between the mold and first said valve, and means automatically opening the last said valve when the mold bottom is dipped and closing it at other times.

20. In combination, a turret mounted upon a vertical axis, a plurality of molds carried by the turret in an annular series, each mold comprising two halves mating in a vertical 10 plane, means to open the mold and means to thereafter swing one of the sections, carrying a casting in its mold cavity, face down, a female die beneath the face-downward position of the mold section, means for releasing 15 the casting from the mold section while the section is face-downward, and a male die

adapted to force the casting through the female die.

21. In combination, a mold having an inlet opening in its bottom, means for moving 20 the mold in an annular path, a container for molten metal below a portion of the path, means to dip the bottom of the mold into the molten metal while over the container, means to evacuate the mold cavity while the mold 25 bottom is dipped, means to open the mold and discharge the casting, and means to subsequently cool the bottom of the mold relatively to the body of the mold.

In testimony whereof, I have hereunto 30 signed my name to this specification.

AUGUST KADOW.
